Primary Examiner — T Chase Nelson*Assistant Examiner* — Jamillah Khalil Abdullah(74) *Attorney, Agent, or Firm* — Merchant & Gould P.C.(57) **CLAIM**

The ornamental design for a footwear, as shown and described.

DESCRIPTION

FIG. 1 is a front, top and right side perspective view of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof; and,

FIG. 6 is a top plan view thereof.

The bold broken lines represent stitching and are part of the claimed design. The remaining broken lines in the drawings show portions that form no part of the claimed design.

1 Claim, 5 Drawing Sheets(56)
